UNITED STATES PATENT OFFICE.

DAVID J. STRICKLAND, OF CLEVELAND, OHIO.

BRICK-HANDLING DEVICE.

Application filed August 21, 1924. Serial No. 733,345.

This invention relates generally to brick showing driving arrangement; Fig. 15 is a detail view of the clutch mechanism used to rotate the inverter; Fig. 16 is a view similar to Fig. 15 showing how the clutch is automatically released every 180°; Fig. 17 is a sectional view taken on the line 17—17 of Fig. 16; Fig. 18 is a side elevation of Fig. 16; Fig. 19 is a detail in elevation showing the bumper mechanism; Fig. 20 is an elevation looking from the left of Fig. 19; Fig. 21 is a section on the line 21—21 of Fig. 19; Fig. 22 is a view similar to Fig. 7 showing the parts in a different position; Fig. 23 is a detail showing the mechanism for positioning the inverted molds over the lower-
ing table; Fig. 24 is a detail sectional view of the type of shear pin used at various places on the machine; Figs. 25 and 26 are detail views of a brake mechanism used on the inverter shafts to keep them from spin-
ning; Fig. 27 is a side elevation of means for locking the inverters in their discharge positions; Fig. 28 is a plan view of the parts shown in Fig. 27; and Figs. 29 to 33 inclusive are detail views of the die and smoother plate and the manner of mounting the same.

5 The object of the invention is to provide a strong, durable and comparatively simple machine which will bump the molds at the ends as they emerge from the pressing machine and then invert the palleted mold so as to deposit the molded bricks upon the pallet and convey them to the drier while the inverted mold is carried back sanded, reversed and placed in position to receive another charge of clay.

10 With this main object in view and certain minor objects which will appear hereinafter the invention consists in the novel features of construction and combination all of which will be fully described herein-
after and set forth in the appended claims.

In the drawings forming a part of the specification Fig. 1 is a side view of the pug mill and what may be termed the forward portion of the brick handling machine opera-
25 tively connected therewith; Fig. 2 is a similar view showing the remainder or rear end of the side brick handling device; Fig. 3 is a plan view of the forward end of a brick handling machine, certain parts being omitted for clarity of illustration and Fig. 4 is a similar view showing the remainder or rear end of said machine; Fig. 5 is a detail view partly in section showing the means for elevating the reversed and sanded mold and means for pushing such reversed and sanded mold beneath the die of the pug mill; Fig. 6 is a view similar to Fig. 5 showing the upper inverter, pallet lowering table, sander and lower inverter, these parts being adja-
30 cent those shown in Fig. 5; Fig. 7 is a sectional view of the rear part of the machine, showing the means for lowering the emptied mold onto the mechanism by which it is fed back into the sander; Fig. 8 is a view similar to Fig. 5, showing the parts in a different position; Fig. 9 is a detail sectional view showing the upper inverter and the pallet lowering table in different position than shown in Fig. 5; Fig. 10 is a transverse sec-
35 tional view taken to the rear of and looking toward the pallet lowering table; Fig. 11 is a vertical sectional view of the upper in-
40 verter; Fig. 12 is a top plan view of the in-
45 verter and Fig. 13 is an end elevation of the inverter; Fig. 14 is a diagrammatic view
50 taken to the rear of and looking toward the pallet lowering table; Fig. 15 is a detail view of the clutch mechanism used to rotate the inverter; Fig. 16 is a view similar to Fig. 15 showing how the clutch is automatically released every 180°; Fig. 17 is a sectional view taken on the line 17—17 of Fig. 16; Fig. 18 is a side elevation of Fig. 16; Fig. 19 is a detail in elevation showing the bumper mechanism; Fig. 20 is an elevation looking from the left of Fig. 19; Fig. 21 is a section on the line 21—21 of Fig. 19; Fig. 22 is a view similar to Fig. 7 showing the parts in a different position; Fig. 23 is a detail showing the mechanism for positioning the inverted molds over the lower-
55 ing table; Fig. 24 is a detail sectional view of the type of shear pin used at various places on the machine; Figs. 25 and 26 are detail views of a brake mechanism used on the inverter shafts to keep them from spin-
60 ning; Fig. 27 is a side elevation of means for locking the inverters in their discharge positions; Fig. 28 is a plan view of the parts shown in Fig. 27; and Figs. 29 to 33 inclusive are detail views of the die and smoother plate and the manner of mounting the same.

65 Referring to the drawings, 10 indicates a pug mill or other type of brick making machine which is provided with a die 11 at its delivery end for the purpose of directing the clay into the mold 12 which is arranged beneath the die, said mold resting upon a series of rollers 13 journaled in the main frame 14, the mold being projected beneath the die 11 by means hereinafter explained. 70 After the mold is filled, it is pushed along by the next succeeding mold and while resting between the guides 16 each end of the mold is subjected to a bumping or hammering by means of a hammer 17 mounted upon one end of a rock shaft 18 which carries an arm 18^a which is engaged by the cam 19 mounted upon a shaft 20, the cam causing the arm to rock back and forth at definite intervals for the purpose of striking the end of the mold. 75 This shaft 20 which carries the cam upon the exterior thereof turns at stated intervals for the purpose of and in the manner hereinafter set forth.

80 The blow of the hammer is adjustable to a limited extent, this adjustment being accomplished by means of a threaded rod 18^b having a hand wheel 18^c at the outer end and working upon this threaded rod is an arm 18^e through which is also passed a rod 85

90

95

100

105

110

18^d and between the arm 18^c and the end of the rod 18^a there is a coil spring 18^h. The outer end of the rod 18^a passes through a lug 18^e mounted on the shaft 18 and a knife blade washer 18^f is held in contact with the lug 18^e by means of nuts 18^g, this knife blade washer permitting the rocking movement of the arm which exerts the necessary pressure due to the position of the arm 18^c and the amount of compression under which the spring 18^h is placed.

The arm 18^c is held in an upright position by a rod 18^m which passes through a boss 18ⁿ on one side of the arm 18^c. By rotating the rod 18^b by the hand wheel 18^p the arm 18^c is moved back or forth on the rods 18^b and 18^m thus increasing or decreasing the compression of the spring 18^h which will change the blow of the hammer 17.

20 After the mold has been bumped or knocked, a pallet of metal or wood is placed upon the bricks contained within the mold. The bumped and palleted mold is pushed along the table and into an inverter which turns through one-half of a revolution at each half rotation of the shaft 21 upon which the inverter is mounted and as the inverter makes one-half revolution, it is obvious that the filled and palleted mold will be inverted, that is the pallet being on the bottom and the mold upon the top, this inversion being due to discharging the bricks from the mold.

22 The inverter comprises a central portion 22 and similar upper and lower portions 22^a bolted to the central portion 22, the upper and lower portions being arranged in reverse order as shown so that oppositely disposed and offset spaces are provided into which the filled and palleted mold is pushed and ejected. The central portion 22 is keyed to the shaft 21 and working through the shaft 21 and through the central portion 22 is the ejector rod 22^b having ejector fingers 22^c at each end thereof, these fingers working between the guide shoes 22^d, these shoes being spaced apart just sufficiently to permit the palleted mold to slide freely into and out of the recess. The palleted mold is pushed 40 from the table into the upper compartment of the inverter and in doing so, it comes in contact with the finger 22^c and pushes the same inwardly, this movement of the finger 22^c forcing the rod 22^b through the shaft 21 and forcing or ejecting the inverted mold 50 from the opposite and lower compartment of the inverter.

60 The pallet and inverted mold are pushed upon the table 23 which is carried by a pair of arms 23^a, said arms being in turn pivotally connected to a pair of parallel bars 23^b pivoted at 23^c and beneath the table 23 there are mounted rollers 23^d which contact with cams 23^e mounted upon a shaft 24 which 65 shaft is constantly rotated, and the cam 23^e

is so placed and is of such shape that the table 23 will be placed directly in line with the lower compartment of the ejector so that the pallet and mold can be pushed out upon this table 23. Adjacent the ends of the table 70 23 are provided spaced projecting portions 23^f along which the mold 12 travels and is discharged onto the endless chains 25 traveling around sprockets 25^a mounted upon a shaft 26. The pallet with the bricks thereon, 75 however, is somewhat shorter than the mold and as the table 23 is lowered due to the movement of the cam 23^e, the pallet with the bricks thereon is deposited upon the endless chains 27 from which they are directed to 80 the conveyors 28 by means of which the pallets with the bricks thereon are carried laterally away from the machine as most clearly shown in Fig. 4. These chains 27 pass around the sprockets 27^a upon the shaft 26 85 and a sprocket 27^b upon the shaft 24.

While the mold is held upon the table 23 the bottom of the mold is tapped by means of hammers 29 arranged upon the ends of the arms 29^a, said arms being connected to a shaft 29^b and having a finger 29^c which is actuated by a tappet cam 29^d to trip the hammer arm and cause the hammers to strike upon the bottom of the mold in order to more completely dislodge the bricks therefrom. 95 In order to prevent the hammers striking too sharp a blow, I provide a bar 29^e extending across the frame and supported upon springs 29^f surrounding the rods 29^g. This spring bar tempers the blow and thereby 100 avoids injury to the mold and likewise the bricks.

In order to move the mold and pallet along as they are ejected from the inverter, 105 I provide a pair of pusher arms 30 mounted upon stud shafts 31 said arms having each a finger portion 31^a which is operated upon a cam arm 31^b rigidly mounted upon the shaft 24, and this cam arm 31^b is so placed that at the proper point of revolution of the shaft 110 it engages the finger 31^a moving the pusher arm 30 in the direction indicated and pushing the mold along on the side guides at the same time that the pallet is directed to the table 23.

115 The chains 25 traveling in the direction of the arrow indicated in Fig. 7, move along in the mold guides 32 composed of an angle iron and carry the inverted and empty mold along while the pallet with the bricks thereon is guided off by the conveyor 28, as most clearly shown in Figs. 2 and 4.

120 The chains 25 travel around the sprockets 25^a at one end and sprockets 25^b at the opposite end, the lower flights of the chains 25 passing below the lateral conveyor. When the mold reaches the end of the mold guide 32 as it passes around the sprockets 25^b, it is deposited between the mold receiving and lowering arms 33 and 33^a connected to blocks 125 130

rigidly attached to a cross shaft 33^b, this cross shaft 33^b carrying arms 33^c provided with rollers which engage cams 33^d mounted upon a shaft 34 which also carries sprockets 34^a and around which travels the mold returning chain 35, these chains also traveling around sprockets 35^a mounted upon a shaft 36 which also has another set of sprockets 36^a around which travel the chains 37 the purpose of which will appear hereinafter.

The mold is carried down the mold guide and delivered to the mold receiver and lowerer which, as before stated, is actuated and so timed that it receives the empty mold and 15 deposits the same upon the chain 35 traveling in the direction indicated in Figs. 2 and 7 and from the chain 35 it is discharged to the chain 37 traveling in the same direction, and this chain 37 passes over the top of the 20 sand box 38 in which are mounted the rotary beater arms 38^a which stir up the sand and throw it upwardly with such force as to thoroughly sand the interior of the inverted mold.

25 The chains 37 pass around sprockets 37^a mounted upon a shaft 38^b and these chains passing around the sprockets 37^a are carried down through a suitable guide 37^b under the sand box 38. Mounted upon the 30 shaft 38^b there are also sprockets 38^a for driving the chains 39 which feed the inverted and sanded mold into the mold reverser 40 which is mounted upon the shaft 20 and which has the oppositely disposed compartments 40^b into which the inverted mold is introduced and from which it is ejected 35 after it has been reversed and in connection with this mold reverser I employ an ejector rod 40^c carrying the finger at the outer end, this rod 40^c working through the shaft 20 and it is obvious that, as the mold is carried across the sander and fed into one of the compartments 40^b, the mold which is in the opposite compartment 40^b will be ejected 40 therefrom and transferred to the endless chains 39 which travel also around sprockets 39^a mounted upon a shaft 41 which also carries a sprocket 41^a around which travels a chain 41^b which travels also around a 45 sprocket 41^c mounted upon the end of the pug mill shaft 42.

As the mold is carried along the upper flights of the endless chains 39, it is lifted 50 upwardly by the mold lifter 43 carried at the end of a rocker arm 44 mounted upon a rock shaft 44^a and having a rocker arm 44^b carrying a roller which is engaged by the cam 44^c mounted upon the shaft 41 and the arm 44 also has an extension 44^d from which 55 is suspended a weight 44^e so that between the cam and the weight the mold lifter 43 will be moved vertically upwardly and maintained in proper relation through the medium of the parallel link rod 43^a pivotally connected to the mold lifter 43 and rig-

idly connected to the rock shaft 43^b. The mold is lifted upwardly into line with a horizontally movable pusher 45 which pushes the same horizontally beneath the die of the pug mill.

The mold pusher 45 travels between the guide rolls 45^a and is actuated by a rocker arm 45^b carried by a rock shaft 45^c mounted upon the frame of the pug mill and having a crank arm 45^d at its outer end which is 50 connected to a pitman 45^e worked from the crank or rocker arm 45^f operated from the pug mill. The shaft 42 is constantly rotating and consequently the shaft 41.

The shaft 24 is also constantly rotating but the shaft 21 makes only a half revolution at a time and this I accomplish by arranging upon one end of the shaft 24 a sprocket 47 around which travels a chain 48 which in turn operates a sprocket 49 55 mounted upon the end of the shaft 21. The sprocket 47 is loose upon the shaft 24. Rigidly connected to the shaft 24, however, is a bifurcated arm 50 between which is pivoted a pawl 51, this pawl 51 having a finger 51^a and the arm 50 is provided with a finger 50^a in line with the finger 51^a and between the fingers 50^a and 51^a I arrange a coil spring 52.

The sprocket carries two lugs 53 spaced 180° apart as most clearly shown in Figs. 15 and 16 and when the shaft is rotating in the direction indicated the lateral finger 51^b of the pawl 51 contacts with the lug 53 and carries the sprocket around until the end of the pawl 51 comes in contact with a roller 54 journaled upon a stud projecting laterally from the frame and when the pawl rides over the roller 54, the laterally projecting finger 51^b is thrown out of disengagement and the arm with its pawl continues around until the next lug 53 is picked up and the operation is continued as previously described.

This causes the shaft 24 to impart an intermittent motion to the sprocket 47 and this sprocket in turn imparts the intermittent motion to the sprocket 49 through the medium of the chain 48 and in this manner the inverter is given a half rotation at the proper determined time.

The tappets 29^b are mounted upon a shaft 29ⁱ which shaft has a sprocket 29^k at its outer end around which travels the sprocket chain 29ⁱ which receives its power from the sprocket 29^m mounted upon the end of the shaft 34.

Upon one end of the shaft 21 there is arranged a brake drum 55 upon which bears a brake band 56 fastened at 56^a to the frame and carrying a weight 56^b at its opposite end, this brake drum and band serving to hold the inverter in its proper position when at rest. The mold reverser 40 which is mounted on the shaft 20 is also intended to 125 130

operate only at predetermined intervals and one-half revolution at a time and this is accomplished by providing the shaft 20 with a sprocket exactly the same as the actuating mechanism previously described connected to the shaft 24 for actuating the sprocket 47.

In connection with the shaft 20 I provide a disk 57 having notches 57^a at diametrically opposite points into which drop the pawls 57^b carried at the end of an arm 57^c mounted upon a rock shaft 57^d and having a depending finger 57^e which contacts with a cam 57^f mounted upon the shaft 38, this cam being so shaped and arranged that the finger 57^e will be operated upon to rock the shaft 57^d in order to lift the pawls at the proper time to permit the shaft 20 to be rotated and at the completion of the half turn the pawls will drop by gravity and arrest the further movement of the shaft so that the reverser will be held in its proper position. Upon the end of shaft 36 there is mounted a gear 58 which meshes with a similar gear 59, this gear 59 being mounted upon a shaft 60 and upon the opposite end of this shaft there is mounted a sprocket 60^a which drives the sprocket chain 61 which in turn drives the sprocket mounted upon the end of the shaft 24.

The sand beaters 38^a are mounted upon shafts 38^b and these shafts are connected by sprockets and a chain 38^c, and one of the shafts 38^b is driven by a chain 38^d, from the shaft 38.

It will of course be understood that the frame which carries all the various mechanisms previously described can be built in any suitable manner to accommodate the various features of construction and certain changes or variations can of course be made in order to accommodate various arrangements which might be made without departing from the broad principle of the invention.

The die 11 which is inserted in the pug mill has a slight vertical movement in order to avoid breakage and this is accomplished by making the die with the flange 11^a which fits into a groove or recess 11^b of sufficient depth to permit a limited up and down movement of the die. The side of the pug mill is cut away as indicated at 10^a and across this opening I arrange a plate 10^b to the inner face of which is riveted an angle iron 10^c to the horizontal arm of which is secured the smoothing blade 10^d which contacts with the upper edge of the mold and smooths off the upper face of the brick as it is pushed from beneath the die and smoothing blade.

The plate 10^b is preferably formed of channel iron but the flanges thereof are cut away adjacent the ends. This plate is connected to the pug mill casing by means of

bolts 10^e extending horizontally outwardly and having the nuts 10^f secured thereon, there being vertical bars 10^g through which the bolts pass and which contact with the plate 10^b and hold the plate in proper position, but in order to prevent the plate being fastened so securely as to prevent a slight vertical movement, I provide spacing collars 10^h upon the bolts and between the bars 10^g and the pug mill casing, there being elongated openings in the plate to permit a limited vertical movement in order to avoid breakage in case any obstruction should be present in the brick and which will not yield to the action of the smoothing blade or knife.

The smoothing blade or knife is of the full width of the mold and the die is somewhat wider than the mold and the plate 10^b is of sufficient width to permit the bolts to be arranged at the sides of the pug mill and therefore will not interfere with the proper connection between the plate and pug mill.

From the foregoing description taken in connection with the drawings, it will be seen that I first force the clay into the mold and then push the filled mold onto a suitable table where the ends of the molds are bumped or knocked, and then the mold with a pallet placed thereon is moved along to the inverter. Here the palleted mold is turned completely over, placing the pallet upon the bottom so that the bricks can escape from the mold and remain upon the pallet.

As the inverted mold is discharged from the inverter, the bottom thereof is tapped so that in connection with the end bumping and the bottom tapping, the bricks will be readily dislodged. The pallet with the bricks thereon is then carried off laterally while the inverted mold is carried down and deposited in a mold receiving and lowering device which places it upon a return chain. This return chain carries the mold across the top of a sanding device embodying a rapidly rotating sand beater which throws the sand up into the inverted mold. The sanded mold is then fed into a mold reversing device which is also given a half movement at predetermined times, reversing the inverted mold and placing it proper side up. The reversed mold is then delivered to a mold lifting device which lifts it up into the plane of the table and from which it is pushed at the proper time beneath the die of the pug mill.

It will of course be understood that a number of molds are going through the machine at the same time and consequently one mold can be employed to help feed the other molds along in feeding the mold beneath the pug mill die and they will also be practically in contact with each other across the

top of the sander so that a number of molds in reality constitute the top of the sanding device.

All of the various parts are strong and durable and the parts which require synchronous action are reduced to a minimum and so simplified as to avoid the necessity of a highly skilled mechanic to install and maintain the device.

10 Having thus described my invention, what I claim is:—

1. In a machine of the kind described, the combination with means for moving a filled mold from beneath a die, of means for striking the ends of said mold, means for inverting said mold with pallet, and a vertically movable guide in advance of said inverter.

2. In a machine of the kind described, the combination with means for moving a filled mold from beneath a die, of means for striking the ends of said mold, means for inverting said mold with pallet, and a vertically movable guide in advance of said inverter, and means for tapping the bottom of the inverted mold while held upon said guide.

3. In a machine of the kind described, the combination with means for moving a filled mold from beneath a die, of means for striking the ends of said mold, means for inverting said mold with pallet, and a vertically movable guide in advance of said inverter, and means for moving said pallet and mold and separate means for respectively receiving said pallets and mold.

4. In a machine of the kind described, the combination with means for moving a filled mold from beneath a die, of means for striking the ends of said mold, means for inverting said mold with pallet, and a vertically movable guide in advance of said inverter, and means for tapping the bottom of the inverted mold while held upon said guide, and means for moving said pallet and mold and separate means for respectively receiving said pallet and mold.

5. In a machine of the kind described, the combination with a mold inverter, of a vertically movable guide, a pallet conveyor, a mold conveyor, and means for moving said mold and pallet to their respective conveyors, and a rocking mold receiver arranged at the end of the mold conveyor.

6. In a machine of the kind described, the combination with a mold inverter, of a vertically movable guide, a pallet conveyor, a mold conveyor, and means for moving said mold and pallet to their respective conveyors, a rocking mold receiver arranged at the end of the mold conveyor, and a return conveyor on which the rocking receiver deposits the mold.

7. In a machine of the kind described, the combination with a mold inverter, of

a vertically movable guide, a pallet conveyor, a mold conveyor, and means for moving said mold and pallet to their respective conveyors, a rocking mold receiver arranged at the end of the mold conveyor, a return conveyor on which the rocking receiver deposits the mold, and a sander over which the return conveyor carries said mold.

8. In a machine of the kind described, the combination with a mold and pallet inverter, of a mold conveyor and a pallet conveyor and means for moving said pallet and mold to their respective conveyors, a rocking mold receiver, a return conveyor on which the mold receiver deposits the mold, a sander over which said mold is carried, and a mold reverser arranged at the end of the return conveyor for reversing the sanded mold.

9. In a machine of the kind described, the combination with a mold and pallet inverter, of a mold conveyor and a pallet conveyor and means for moving said pallet and mold to their respective conveyors, a rocking mold receiver, a return conveyor on which the mold receiver deposits the mold, a sander over which said mold is carried, and a mold reverser arranged at the end of the return conveyor for reversing the sanded mold, and means for moving the sanded mold into the reverser.

10. In a machine of the kind described, the combination with a mold and pallet inverter, of a mold conveyor and a pallet conveyor and means for moving said pallet and mold to their respective conveyors, a rocking mold receiver, a return conveyor on which the mold receiver deposits the mold, a sander over which said mold is carried, a mold reverser arranged at the end of the return conveyor for reversing the sanded mold, said inverter having an ejector for ejecting the inverted sanded mold.

11. In a machine of the kind described, the combination with a mold and pallet inverter, of a mold conveyor and a pallet conveyor and means for moving said pallet and mold to their respective conveyors, a rocking mold receiver, a return conveyor on which the mold receiver deposits the mold, a sander over which said mold is carried, a mold reverser arranged at the end of the return conveyor for reversing the sanded mold, and means moving the sanded mold into the reverser, said inverter having an ejector for ejecting the inverted sanded mold.

12. In a device of the kind described, the combination with a mold reverser, of means for carrying said mold away from said reverser, a lifter for said mold, parallel arms connected to said lifter and means raising and lowering said arms.

13. In a device of the kind described, the combination with a mold reverser, of means

for carrying said mold away from said reverser, a lifter for said mold, parallel arms connected to said lifter, means raising and lowering said arms, and a stop for arresting the mold above the lifter.

14. The combination with a rotary shaft, of an inverter connected thereto and comprising a central portion and oppositely disposed portions connected thereto, and an 10 ejector working through the shaft and between the oppositely disposed portions.

15. The combination with a rotary shaft, of an inverter connected thereto and comprising a central portion and oppositely 15 disposed portions connected thereto, said portions being provided with shoes, and an ejector comprising a rod working through the shaft and pushing at the ends of said rod and working between the shoes.

16. The combination with a mold conveyor, of a rocking mold receiver at the end of said conveyor, a rocker arm carried by the shaft of said rocker, a cam for actuating said rocker arm and means for rotating said cam.

17. The combination with a mold inverter, of a mold receiving guide arranged in advance of said inverter, a bell crank for moving said mold from said guide, a cam for actuating said bell crank and means for 30 moving said cam.

18. The combination with a mold inverter, of a mold receiving guide, parallel arms

connected to said guide, a cam for moving said guide vertically and means for moving 35 said cam.

19. The combination with a mold receiving table, of knockers for striking the ends of said mold, a cam for actuating said knockers, means for moving said cam, and 40 adjustable means for regulating the blow of said knockers.

20. The combination with a mold inverter, of a constantly rotating shaft, and means interposed between said shaft and 45 inverter for intermittently moving said inverter.

21. The combination with a mold inverter, of a vertically movable mold receiving guide in advance of said inverter, a rotary 50 shaft, means connected with said shaft for moving said guide and means connected with said shaft for intermittently moving the inverter.

22. The combination with a mold inverter, of a vertically movable guide, a rotary shaft, means connected with said shaft for intermittently moving said guide, a pusher for moving the mold from the guide, and means connected with the shaft for intermittently moving said pusher, and means 60 connected with the shaft for intermittently moving the inverter.

In testimony whereof, I hereunto affix my signature.

DAVID J. STRICKLAND.
